UNITED STATES PATENT OFFICE.

WILLIAM M. SHANNON AND GEORGE K. TAYLOR, OF COLUMBIA, SOUTH CAROLINA.

COMBINED LOCK AND ELECTRIC SWITCH.

No. 880,167.

Specification of Letters Patent.

Patented Feb. 25, 1908.

Application filed July 1, 1907. Serial No. 381,741.

To all whom it may concern:

Be it known that we, WILLIAM M. SHANNON and GEORGE K. TAYLOR, both citizens of the United States, and both residing in 5 Columbia, county of Richland, State of South Carolina, have invented certain new and useful Improvements in a Combined Lock and Electric Switch; and we do hereby 10 decree the following to be a full, clear, and exact description of the invention, such as will enable others skilled in the art to which it appertains to make and use the same.

The invention relates to a door lock switch for electric lights and the like, and is essentially intended to provide a lock-controlled switch for offices and the like, by means of which the lighting circuits in a room or apartment controlled by the door will be opened or disconnected when the person last 20 leaving the room or apartment closes the door, after having first thrown on the dead latch to prevent the door being opened from the outside, except by a person having the proper key. This object is attained by arranging one of the push buttons which controls the operation of the lock by means of the key and the knob respectively, so that said push button projects beyond the face of the lock sufficiently to engage the movable 25 member of an electric switch located in the door jamb, and preferably behind the lock strike, the strike being recessed or cut away sufficiently to permit the passage of the projecting end of the push button.

30 The invention is illustrated in the accompanying drawings, in which,

Figure 1 is a vertical section through a well known form of cylinder lock and its strike, showing the relation of the switch to 40 the lock. Fig. 2 is an edge view of the door. Fig. 3 is a horizontal section through the door and door jamb, illustrating the coöperation of the push button, and the switch when the door is closed. Fig. 4 is a corresponding 45 view showing the door in the operation of closing. Fig. 5 is a perspective view of the door in the operation of closing.

Referring to the drawings, *a* indicates the door, and *b* the jamb or casing with which the 50 same operates. Mounted in the edge of the door in the usual manner is the lock, which is shown as a mortise cylinder lock of the well known Yale type, although it is to be understood, of course, that the invention is not 55 limited to any particular form of door lock, but may be applied to locks generally, where

the lock is provided with the usual form of push button for controlling the dead latch. In the form of lock shown, 1 indicates the casing within which is slidably mounted the 60 latch bolt 2, which coöperates with the strike 15 mounted in the door jamb. The latch bolt 2 is operated by the usual form of divided hub 9, which latter is of the ordinary construction to permit the bolt to be operated by the knob at all times from the inside of the room, but to permit said bolt to be operated by the knob from the outside only when the dead latch is off, a key being required to retract the bolt when the dead 65 latch is on.

Mounted in the lock casing is the usual form of cylinder 4, provided with a wing 5 which operates the bolt to retract the latter by means of pivoted dogs 6 and 7.

75 Slidably mounted in the casing are two push buttons 8 and 11, the ends of which engage and are adapted to be projected through suitable holes in the face of the lock, which lies flush with the edge of the door. The 80 inner end of push button 8 engages with a notch 9, in one member of the hub 10, to prevent the bolt 2 being operated by the knob from the outside, when said push button 8 has been shoved inward. Said 85 bolts 8 and 11 are connected by a lever 13, which is pivoted off center in the casing 1, so as to impart a greater movement to push button 11 than to push button 8, whereby the former will be caused to project some 90 little distance beyond the face of the lock when push button 8 is forced inwardly, but nevertheless to cause the outer end of said push button 11 to lie substantially flush with the face of the lock when said push 95 button 11 has been forced home. Preferably the outer end of push button 11 is made square in cross section as at 11', and coöperates with a square hole in the face of the lock, as shown in Fig. 2.

100 The lock strike 15, which is mounted on the door jamb, in position to coöperate with the latch bolt 2, is cut away or recessed at 17, to permit the passage of end 11' of push button 11 when the latter is advanced. Located in the door jamb, behind the lock strike and secured to a face plate 16, which may be conveniently formed as an angular projection of the lock strike, is a box or casing adapted to contain the switch which 105 controls the circuit to the lights or other electrical apparatus in the room or apartment.

Said switch consists of stationary contacts 25 mounted upon a block of insulation and connected with the leads 26, 26. The movable member of the switch consists of a 5 U-shaped contact having knife blades 24, which coöperate with a stationary contact 25, which U-shaped piece is connected by a spacing block 22 with a sliding bolt 20, which is held in proper alinement in the casing 10 by passing through a suitable orifice in one side thereof and by means of the in-turned ends of the casing which form guides 19 coöoperating with the sides of the spacing block 22, as more particularly illustrated in 15 Fig. 1. The bolt 20 is normally advanced by a helical spring 21 which surrounds the same and is confined between the side wall of the casing and the spacing block 22, so as to hold the bolt in position to cause the 20 movable contacts 24 to engage the fixed contacts 25 and establish the electrical circuits in the room.

The operation of the device is as follows: During the time the room is occupied, push 25 button 11 is usually retracted to permit the door to be opened by the knobs from either the inside or the outside. Under these conditions, the end 11' of said push button 11 lies flush with the face of the lock, viz., it 30 does not project beyond the edge of the door. Plunger 20 under the influence of its spring 21 therefore holds the switch in closed position, whether the door be open or closed. When the room or apartment is vacated, 35 however, push button 8 is forced inward by the person leaving, to prevent the lock being operated by the outside knob, as hereinbefore described. The inward movement of push button 8 causes push button 11 to be 40 moved outward, and, by reason of the greater extent of movement of said push button, the end 11' thereof is projected beyond the face of the lock and in position to pass through the slot or opening 17 in the strike, to engage 45 the forward end of spring plunger 20, so that when the door is completely closed and locked, said plunger 20 has been retracted sufficiently to separate movable contacts 24 from fixed contacts 25 of the switch, to 50 break the circuit. When the door is opened, however, the switch is closed automatically and the circuits are established, and in order to maintain the circuit closed when a person is in the room, it is necessary to throw off 55 the dead latch by forcing said push button 11 inward, which correspondingly moves push button 8 out, so that the end thereof disengages the section of hub 9.

It will be noted that the switch operating 60 mechanism may be applied to any of the ordinary forms of lock without materially

changing the construction of the latter, and that, when the lock and switch are combined in accordance with the invention, it is manifestly impossible for a person leaving an 65 apartment and locking the door after him to leave the lights in the apartment burning.

What we claim as our invention is:—

1. In a door lock switch for electric lighting circuits and the like, the combination with a lock controlling push button which projects beyond the lock face when in advanced position, of a switch located in the door jamb and having a movable member in the path of movement of said push button; 75 whereby the switch is operated by the closing of the door.

2. In a door lock switch for electric lighting circuits and the like, the combination with a pair of push buttons which control the dead latch, one of which buttons projects beyond the lock face when in advanced position, of a switch located in the door jamb having a spring plunger for operating the movable member of the switch and adapted 85 to be engaged by said projecting bolt as the door is closed.

3. In a door lock switch for electric lighting circuits and the like, the combination with the lock having a pair of push buttons to control the operation of the dead latch, one of said push buttons projecting beyond the face of the lock when in advanced position, of an electric switch located behind the lock strike and having a spring plunger carrying the movable contacts and lying in the path of movement of said projecting bolt as the door is closed, said lock strike being recessed adjacent said plunger to permit the 95 passage of the end of the push button. 100

4. In a door lock switch for electric lighting circuits and the like, the combination with the lock having a pair of push buttons to control the operation of the dead latch, one of said push buttons projecting beyond the face of the lock when in advanced position, of an electric switch mounted in the door jamb behind the lock strike, said switch comprising a stationary contact and a movable contact normally engaging each other, 110 said movable contact lying in the path of movement of the projecting push button as the door closes, whereby the electric circuit is broken by the closing of the door.

In testimony whereof we affix our signatures, in presence of two witnesses:

W. M. SHANNON.
GEO. K. TAYLOR.
